OF NEW YORK, N. Y., A CORPORATION OF NEW YORK.

RELIEF AND INTAGLIO PRINTING MACHINE.

1,123,455.

Specification of Letters Patent.

Patented Jan. 5, 1915.

Application filed February 18, 1907. Serial No. 357,837.

To all whom it may concern:

Be it known that I, HENRY A. WISE Wood, a citizen of the United States, residing at New York, in the county of New York and State of New York, have invented a new and useful Relief and Intaglio Printing Machine, of which the following is a specification.

In the printing of photogravures which is 10 done from etched intaglio plates, the title and any other parts in letter-press are run ordinarily at a separate operation, after the intaglio print has been made, thus necessitating two handlings of the work.

15 The principal object of this invention is to provide means whereby a machine at one handling will first print from one set of plates, and thereafter from the other, said plates constituting substantially the same or 20 contiguous surfaces, whereby portions of a picture may be done in intaglio, and other portions super-imposed thereupon in relief, or vice versa. Consequently, a picture may be printed from intaglio surfaces, and the 25 title or surrounding frame or the like printed from relief blocks.

Reference is to be had to the accompanying drawing which is a longitudinal sectional view of a portion of a printing press 30 showing one form in which the invention can be carried out.

In this form the machine is provided with a two revolution impression cylinder *a*, a two-revolution relief plate cylinder *b*, and a 35 two-revolution intaglio plate cylinder *c*. The relief plates are inked by an inking device *d*, and the intaglio shell by an inking device *e* having a scraper *f* of any usual or desired construction.

40 The impression and printing cylinders are designed to be separated so as to move into and out of contact. This is accomplished in any desired way, as by mounting the shaft of the impression cylinder in eccentric journal boxes *p* provided with levers *q* operated through connections *r* in any desired way. By this means the impression cylinder is actuated to rise at each alternate revolution.

45 It will be noticed that as in this construction the cylinders make two revolutions to an impression, the printing cylinders would be double inked if the inking mechanism were not withdrawn during the second revolution of each of the printing plates as

shown. The inking mechanisms *d* and *e*, as indicated in the drawing, are mounted in frames *g* and *h* respectively. These frames being mounted to slide in ways *i* and *k*, and are actuated to move toward and from their 60 respective printing cylinders preferably horizontally. On one revolution of the cylinders they are in contact with their cylinders to ink the same, but on the next revolution they are withdrawn so that the cylinders will not be double inked; that is, inked twice for each impression. It will be understood that on the second revolution the printing cylinders are not in contact with the sheet on the impression cylinder which 65 is delivering at this time. The specific mechanism by which this movement is brought about is relatively unimportant, but I have shown it in the form of gear *l* mounted on the shaft *m* of each of the printing 70 cylinders, this gear being connected with a shaft *n* through a gear *o* to operate the shaft *n* at half the speed of the shaft *m*. On each shaft *n* is a cam or the like which 75 operates the frame on which the inking mechanism is mounted once during each revolution of the shaft, which, in the present instance, makes one revolution for two revolutions of the printing cylinder. This construction may be varied to suit conditions 80 existing.

In this form a continuous shell, preferably of copper can be employed advantageously for the intaglio printing, and the intaglio printing cylinder makes more than 85 one revolution to every impression.

When handling sheets, for which this machine is designed, there is space upon the impression cylinder between the head of one sheet and tail of the next one for the 90 purpose of gripping and delivering, and when the cylinder has a forward delivery at least one idle revolution is made for every sheet in order to deliver it. It will be clear, therefore, that by constructing a printing 95 press in accordance with the principles herein illustrated, the above mentioned advantages will be secured in a simple, convenient and accurate manner.

While I have illustrated and described 100 only one form in which the invention can be constructed, I am aware of the fact that many modifications can be made therein within the spirit of the invention as expressed in the claims. Therefore, I do not 110

wish to be limited to the particular form illustrated, but

What I do claim is:—

1. In a sheet printing machine, the combination of an impression cylinder, a relief printing cylinder, a multi-revolution intaglio printing cylinder, and means for inking said printing cylinders only during alternate revolutions thereof.
2. In a printing machine, the combination of an impression cylinder, a two revolution relief printing cylinder, a two-revolution intaglio printing cylinder, the relief and intaglio printing cylinders contacting with the impression cylinder, and means for inking one of said cylinders during alternate revolutions, said means being inoperative during the remaining revolutions.
3. In a printing machine, the combination of an impression cylinder, two printing cylinders, one carrying a relief printing surface, and the other an intaglio printing surface, an inking device for each cylinder, and means for automatically moving said inking

devices toward and from their respective cylinders. 25

4. In a printing machine, the combination of an impression cylinder, two two-revolution printing cylinders, inking devices for each of said printing cylinders, and means for moving said inking devices into contact with their respective cylinders during one revolution, and out of contact therewith during the next revolution. 30

5. In a printing press, the combination of a two-revolution printing cylinder, an inking device therefor, and means for holding the inking device in contact with the cylinder during one revolution and withdrawing it during the next revolution. 35 40

In testimony whereof I have hereunto set my hand, in the presence of two subscribing witnesses.

H. A. WISE WOOD.
